UNITED STATES PATENT OFFICE.

HARRY HEFFNER, OF CLEVELAND, OHIO.

STOVEPIPE-THIMBLE ATTACHMENT.

1,399,619.

Specification of Letters Patent.

Patented Dec. 6, 1921.

Application filed February 21, 1920. Serial No. 360,348.

To all whom it may concern:

Be it known that I, HARRY HEFFNER, a citizen of the United States, residing at Cleveland, in the county of Cuyahoga and State of Ohio, have invented new and useful Improvements in Stovepipe-Thimble Attachments, of which the following is a specification.

This invention relates to a stove pipe thimble attachment, the thimble being provided with means to limit the insertion of the stove pipe within the thimble, and the collar of the thimble being cut away to provide an opening for the escape of hot air, and forming a loop for connection with a terminal of a pipe holder.

In carrying out my invention, I provide the thimble with an adjustable member, which may be projected any appreciable distance within the chimney flue, this member being utilized to direct the rain water away from the flue opening, thus preventing this water from finding its way through the flue opening to damage the paint or paper upon the wall.

The nature and advantages of the invention will be better understood when the following detail description is taken in connection with the accompanying drawings, the invention residing in the construction, combination and arrangement of parts as claimed.

In the drawings forming part of this application, like numerals of reference indicate similar parts in the several views and wherein:

Figure 1 is a front elevation of the thimble.

Fig. 2 is a vertical sectional view taken therethrough.

Fig. 3 is a perspective view showing the adjustable member associated therewith.

Fig. 4 is a sectional view through a chimney showing a stove pipe elbow associated therewith and with the thimble.

Fig. 5 is a view of the pipe holder.

Fig. 6 is a plan view of the said adjustable member.

Fig. 7 is a side elevation thereof.

Referring to the drawings in detail, 10 indicates the thimble formed at one end to provide the collar 11, the latter terminating to provide an inwardly directed flange 12, adapted to bear against the wall of the chimney A when the thimble is associated with the stove pipe in the manner illustrated in

Fig. 4. Disposed within the thimble 10 is a lug 13 constituting a stop to limit the insertion of the pipe elbow B within the thimble. The collar 11 is cut out at an appropriate point to provide an eye 16 adapted to receive the hook terminal 17 of the pipe holder illustrated in Figs. 4 and 5. This holder consists of a strand of wire or other suitable material terminating at one end to provide the said hook 17, the opposite end defining a loop 18 which is adapted to embrace the vertical portion of the elbow B as clearly shown in Fig. 4. When the collar 11 is stamped to provide the eye 16, an opening 19 is also provided in the collar to permit the escape of hot air from the chamber defined by the space between the chimney A and the collar 11.

Associated with the thimble 10 is a member clearly illustrated in Figs. 3, 6 and 7, this member being substantially semi-cylindrical in cross section to conform to the curvature of the thimble 10. Projecting from the body portion 20 of this member, 75 is an extension 21, having an elongated slot 22 adapted to register with an opening 23 in the thimble for the reception of a bolt 24 having associated therewith a nut 25. The body portion 20 is formed to provide groove 80 26 which extends across the entire transverse area of the member. This member is primarily intended to direct the rain water or the like which comes down the wall of the chimney, away from the pipe receiving 90 opening, with a view of preventing this water from gaining access to the opening and wedging its way in the direction of the wall papers which it would obviously mar or destroy. The water striking the curved 95 body portion 20 of this member is carried downwardly through the chimney, in the direction of the groove 26 which also conveys the water downwardly as will be readily understood. By reason of the slot 22, the 100 member 20 can be adjusted on the thimble 10 as the circumstances may require.

While it is believed that from the foregoing description, the nature and advantages of the invention will be readily apparent, I 105 desire to have it understood, that I do not limit myself to the exact details herein shown and described, inasmuch as such changes may be resorted to when desired as fall within the scope of what is claimed.

If desired, the thimble 10 and the pipe collar 11 may be coated with fire proof ma-

terial as shown in Fig. 2, to prevent burning of the parts to which the thimble projects, should the pipe collar become over-heated.

Having thus described my invention what I claim as new is:—

1. The combination with a stove pipe thimble, of a member carried by the thimble and projected within the flue to direct rain water or the like away from the pipe receiving opening of the chimney.

2. The combination with a stove pipe thimble and means for fixing the thimble to the chimney, of a semi-cylindrical member carried by the thimble and projected within the flue to direct rain water or the like away from the pipe receiving opening of the chimney for the purpose specified.

3. The combination with a stove pipe thimble of a semi-cylindrical member mounted upon the thimble and adjustable with respect thereto to project within the

chimney, means for holding the member fixed in a given position upon the thimble, said member being adapted to direct rain water from the pipe receiving opening of the chimney for the purpose specified.

4. The combination with a stove pipe thimble, of a semi-cylindrical member mounted upon the thimble and adjustable with respect thereto to project within the chimney, said member having a longitudinal slot, a bolt projecting from the thimble and passed through said slot, a nut associated with said bolt for holding the said member fixed relatively to the thimble in its adjusted position, and the projecting extremity of said member being formed with a groove extending from edge to edge for the purpose specified.

In testimony whereof I affix my signature.

HARRY HEFFNER.
